COMBINATION PAINT CONTAINER AND PAINT ROLLER TRAY

William Lyle Fox, Jr., Libertyville, Matthew Edward Hein, Elgin, and John Robert Platt, Crystal Lake, Ill., assignors to American Can Company, New York, N.Y., a corporation of New Jersey

Filed Oct. 5, 1967, Ser. No. 8,876

Term of patent 14 years

(Cl. D64—18)

Fig. 1

Fig. 2

Fig. 4

Fig. 3

Fig. 5

FIGURE 1 is a perspective view of a combination paint container and paint roller tray showing our new design;

FIGURE 2 is a plan view thereof;

FIGURE 3 is a side elevational view thereof;

FIGURE 4 is a rear elevational view thereof; and

FIGURE 5 is a fragmentary perspective view, representing a modified form of the design shown in FIGURES 1-4.

We claim:

The ornamental design for a combination paint container and paint roller tray, substantially as shown and described.
